CLAIM

The ornamental design for a protective hang cover skin for electronic device, as shown and described.

DESCRIPTION

FIG. 1 is a front, top and right perspective view of protective hang cover skin for electronic device showing claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a rear, bottom and right perspective view thereof; and,

FIG. 9 is a front, top and right perspective view thereof, in a reduced scale, with a top portion open in use.

The broken lines shown in FIG. 3 depict a portion of the protective hang cover skin, but form no part of the claimed design. The broken lines shown in FIG. 10 depict environment and form no part of the claimed design.

1 Claim, 8 Drawing Sheets
